Arthur N. Nadelson

ATTORNEY

UNITED STATES PATENT OFFICE

2,419,416

HOLDER AND WARMER FOR LIQUID CONTAINERS

Samuel J. Mustain, Newark, N. J.

Application August 15, 1944, Serial No. 549,614

3 Claims. (Cl. 126—246)

1

This invention relates to holders for liquid containers such as bottles or tumblers, whereby the potable liquid therein may be continued hot or cold, as the case might be. More particularly, the holder of the invention is for holding a tumbler of either hard or soft drink under conditions whereby the drink substantially retains either its heat or its coldness. The holder may also be used for a bottle of potable liquid such as beer, or a bottle of milk such as is used by infants.

The object of the invention is to devise a holder of material that is a poor heat conductor, such as of plastic, from which the holder can be molded, and a metallic liner for the plastic material that is an excellent heat conductor, into which liner the tumbler or bottle fits removably and seats on a disc in the bottom of the liner that also is a good heat conductor. Another object of the invention is to devise the liner so that it will automatically accommodate tumblers or bottles of different diameters.

The invention is capable of embodiment in a number of different manifestations, but that one which to the best of my present knowledge is the most desirable, is shown in the accompanying drawings, in which

Figure 1 is a partial vertical sectional view with parts broken away.

Figure 2 is a top view or plan of same.

Figure 3 is a perspective view of a metallic liner which rests within a holder or outer casing.

Figure 4 is a top view or plan of the metallic liner, with part partly broken away.

Figure 5 is an enlarged detail view, and

Figure 6 is a detailed view, in perspective, of a heating or cooling unit or disc adapted to rest within the metallic liner at the lower edge thereof and upon protuberances formed upon the inside bottom of the holder.

In the drawings, 10 designates a holder or casing made of a substance having a poor heat conducting quality, preferably plastic or other non-metallic substance, and formed with an annular projecting base 11 and a bottom portion 12 upon which there are formed protuberances or spacer buttons 13.

Resting within said holder is a metallic heat conducting liner or jacket 14, which, in order to accommodate beverage containers of different diameters, is split at 15 to form an overlapping sliding edge. The upper edge of said liner is formed with an annular flange or edge 16 under and against which there is provided a sealing and spacing ring 17, of cork or other resilient material. The metallic liner is preferably bottomless and rests within the holder upon the base portion 12, and by means of the sealing ring 17 is spaced from the side of the holder to form an air space 18 which functions as an insulating

2

means between the holder and the metallic jacket or liner.

A disc 19 of suitable heat conducting material such as aluminum, is seated within the holder 5 and rests at the bottom thereof upon the protuberances 13, thus providing an insulating air space 20 between the bottom of the disc 19 and the bottom portion 12 of the holder. The disc is formed with a depressed portion 21 having a cross-bar 22 which provides a grabbing means for lifting the disc out of the holder.

A beverage or edible substance such as ice cream or a salad, may be contained in a glass vessel 23 or similar container such as a bottle 15 while the container is held within the holder and rests upon the disc 19.

The disc 19 may be heated, or chilled, according to desire and thereupon placed in position within the holder where its heat or cold will be conducted through the bottom of the liquid container and through the metallic liner as well as through the sides of the liquid container to prolong retention of either the hot or cold temperature, as the case may be, of the liquid in the container.

While the illustrations and description show and set forth a device especially designed to hold an ordinary glass, containing liquid, it will be obvious that without departing from the principle of the invention the shape of the holder may be so modified that containers other than a glass may be held therein, as for instance, beverage bottles, babies' nursing bottles, bowls for holding foods, etc.

35 It is not intended, therefore, to limit this invention to the particular form shown and described, but to include within the scope of this invention as defined by the claims hereof, other forms for both liquids and solids.

40 I claim:

1. A liquid holder comprising a cup-shaped holder interiorly tapered inwardly from top to bottom, a liquid-holding vessel similarly tapered and adapted to be seated in the holder, a heat-conducting element between the vessel and the bottom of the holder, an expansible open-ended liner similarly tapered having a discontinuous laterally extending flange at its upper end and disposed between the holder and the vessel 45 while surrounding and frictionally engaging both vessel and heat-conducting element in heat-exchange contact, and a resilient ring extending in air-sealing relationship between the inside of the holder and both the flange and the outer wall 50 of the liner.

2. A liquid holder according to claim 1 where-in the liner is of heat-conducting material.

3. A liquid holder comprising a cup-shaped holder interiorly tapered inwardly from top to bottom, a liquid-holding vessel adapted to be

seated in the holder, a heat-conducting element between the vessel and the bottom of the holder, a heat-conducting cylindrical liner disposed between the holder and the vessel while surrounding and frictionally engaging both vessel and heat-conducting element while the latter is in direct heat-exchange relationship with the bottom of the vessel and in indirect heat-exchange relationship with the side of the vessel through the medium of the liner, and resilient means for sealing the liner in place in the holder.

SAMUEL J. MUSTAIN.
